SMOKING PIPE OR SIMILAR ARTICLE

Mohammed Aslam Zia, Karachi, Pakistan (% Pakistan
Restaurant, Pakistan Pavilion, New York's World Fair,
Flushing, N.Y.)

Filed May 27, 1964, Ser. No. 80,173

Term of patent 3½ years

(Cl. D85—8)

FIG. 2

I claim:

The ornamental design for a smoking pipe or similar article, as shown.
